PUSH-PULL AMPLIFIER CIRCUIT

Loy E. Barton, Collingswood, N. J., assignor, by
mesne assignments, to Pennsylvania Patents,
Inc., Carson City, Nev., a corporation of
Nevada

Application October 16, 1937, Serial No. 169,491

13 Claims. (Cl. 179—171)

This invention relates to radio receiving systems and more particularly to circuits for use in radio receivers and the like wherein it is desired to form, in response to an input signal, a corresponding power output signal having a minimum of distortion. The frequency range of the input signal may be quite wide and may extend over the entire audio frequency range.

One object of the invention is to provide a stable push-pull Class A amplifier in which one output tube is self-excited, that is the driving voltage for the said tube is obtained from the output circuit.

Another object of the invention is to provide a stable push-pull Class A output system requiring no input transformers or phase-inverter tubes, and in which the full available Class A output of each tube may be supplied to the output circuit.

Other objects and features of the invention will be apparent from a consideration of the two figures of the drawing of which

Fig. 1 illustrates the preferred form of the invention; and

Fig. 2 is a modification thereof.

It will be understood, however, that the invention is capable of modification and is not limited to the specific form shown.

Referring now to Fig. 1, the space discharge tubes V_1 and V_2 are power output tubes of the type commonly employed in conventional radio receivers. These tubes may be either triodes or pentodes or "beam" type output tubes, although preferably pentode or "beam" type tubes are employed. The tube V_3 serves as the driver tube for one of the two output tubes. A signal source E supplies the desired input signal to tube V_3 . The signal source may be of any suitable character, for example, it may be a detector, a microphone, a phonograph pick-up, etc. The output circuits for tubes V_1 and V_2 may comprise the two portions of the center-tapped primary P of the transformer T , whose secondary S may be connected to some suitable utilization means, such as the loud speaker L_S . It will be understood that any suitable utilization means may be employed.

Signal from the output circuit of the tube V_3 may be built up across its plate load impedance R_1 and supplied to the control grid of tube V_1 by means of the coupling condenser C_1 and the grid-leak resistance R_2 . The input signal for the tube V_2 may be obtained by means of the voltage divider circuit R_3R_4 which is connected to the side of the primary P opposite from that to which the anode of tube V_2 is connected.

Disregarding for the present the resistance R_5 which will be discussed later, it will be apparent that the input signal supplied to the control grid of tube V_1 will cause an amplified signal of opposite phase to appear across that portion of the center-tapped primary P which is connected to tube V_1 . This amplified signal is supplied through the voltage divider R_3R_4 to the control grid of V_2 , causing a signal of opposite phase to appear across that portion of the center-tapped primary P which is connected to the output circuit of tube V_2 . Thus, there are produced in the respective output circuits of tubes V_1 and V_2 signals which are of opposite phase with respect to each other.

The circuit described thus far is not useful for the amplification of a signal such as an audio signal, due to the fact that such circuit will oscillate at its natural frequency unless the signal supplied to tube V_2 is very much smaller than that supplied to tube V_1 . Considering for the moment the circuit including only the tube V_2 , it will be observed that the output signal from tube V_2 will form across the voltage dividing network R_3R_4 a signal of equal amplitude but of opposite phase. A portion of this signal is supplied to the control grid of tube V_2 , causing the tube to oscillate when a sufficient portion of the output signal is fed back. In fact, such a circuit has been employed as an oscillator. On the other hand, if the portion of the signal fed back to the control grid of tube V_2 is insufficient to cause the circuit to oscillate, the amount of power supplied by the tube V_2 will be negligible compared to that which it is capable of supplying or that which is obtained from tube V_1 . Obviously, in such case the tube V_2 would serve no useful purpose.

By the present invention, the maximum available Class A output is obtained from tube V_2 and at the same time, the circuit is prevented from oscillating and is caused to reproduce faithfully the input signal supplied to it. In accordance with the invention, a degenerative connection is provided between the output circuit and the input circuit of tube V_1 . A degenerative connection is one in which a portion of the output signal is fed back to the input circuit in such phase relation that a current is caused to flow in the output circuit in such direction as to oppose the voltage causing it and to lower the effective output impedance of the degenerated amplifier.

Such connection may take different forms but is preferably provided by connecting the resistance R_5 between the anode of tube V_1 and the grid circuit of tube V_1 . It will be noted that by this

connection two direct current paths are provided between the plate of V_3 and the power supply, which has the advantage of minimizing the D. C. voltage drop in the plate circuit external of the tube. When this degenerative connection is employed, the amplifier will not oscillate because the tube V_1 will oppose any tendency of tube V_2 to oscillate. The necessary condition for sustained oscillation is that the signal energy fed to the grid of tube V_2 be sufficient to overcome the losses in the whole circuit. In the absence of the degenerative connection, the tube V_1 appears as a relatively high impedance and does not provide sufficient load in the circuit to prevent oscillations. However, when the degenerative circuit is employed, the effective impedance of the tube V_1 becomes quite low and prevents any oscillations in the circuit, even though the input signal supplied to tube V_2 be as large or larger than that supplied to tube V_1 .

This lowering of the equivalent impedance of tube V_1 may be understood by noting that if the voltage between the cathode and anode of tube V_1 were to change by some small amount, a portion of this voltage in the same phase would be supplied to the input circuit of tube V_1 , which would cause a differential current to flow in the tube in such direction as to prevent the variation in output voltage. Thus the tube V_1 operates as a device to prevent any variation in its cathode-anode voltage, except variations corresponding to the input signal supplied to it, or in other words as a low impedance load for undesired voltage variations. Hence, tube V_1 will prevent tube V_2 from self-oscillating, since in order for self-oscillations to occur, the voltage across the output circuit of tube V_1 must change.

The amount of degeneration may be controlled by varying the ratio of the magnitude of resistance R_5 to the equivalent shunt impedance of R_1 , R_5 and the plate-to-cathode impedance of tube V_3 . The condenser C_1 serves as a blocking condenser to keep the D. C. plate voltage out of the grid circuit. The condenser C_1 may have a negligible impedance at audio frequencies compared to the impedance of R_2 . In general, the use of degeneration will bring about a reduction in the gain of the degenerated stage. In this particular case, however, this effect does not necessarily occur to any great extent. Considering the voltage relations in the input circuit of tube V_1 and including the degenerative path, it will be observed that the effect of the feedback path is to reduce the input impedance of the input circuit including R_2 , R_5 and the tube V_1 , that is the effective impedance which acts as a load for tube V_3 . However, the signal supplied to the grid of tube V_1 will be equal to the signal across R_1 and the magnitude of this signal will be given by a function of the product of the mutual conductance of tube V_3 and the total output load impedance. By proper design, the equivalent input impedance of tube V_1 may be made sufficiently high so that it will, in shunt with R_1 , provide an optimum load impedance for the preceding tube. Hence it will not materially affect the total gain of the circuit.

It will be noted that two condensers C_2 and C_3 are employed in the voltage divider circuit which serves to supply a driving voltage to the input circuit of tube V_2 . The condenser C_2 is in series with resistances R_3 and R_4 and serves as a blocking condenser to keep the D. C. plate voltage out of the grid circuit. The impedance of condenser C_2 may be negligible as compared with that of re-

sistance R_3 at the lowest frequency which it is desired to amplify. The condenser C_3 is in shunt with R_3 and serves to prevent variations with frequency in the proportion of signal fed back. There will be some inter-electrode capacity between the control grid of tube V_2 and its cathode and screen grid, as well as a capacity between the control grid and anode. This capacity is effectively in shunt with resistance R_4 . By providing the condenser C_3 in shunt with the resistance R_3 , and by arranging the ratio of the impedance of the condenser to that of the equivalent input capacity of the tube so that it is proportional to the ratio of resistance R_3 to resistance R_4 , the proportion of signal transferred to the control grid of tube V_2 compared to the total output signal may be made independent of frequency.

By preventing the circuit from regenerating, in accordance with the invention, each tube may be driven so as to obtain the maximum Class A power output. Since tubes V_1 and V_2 are preferably similar, this condition obtains when each tube is supplying the same amount of power and the input signals supplied to tubes V_1 and V_2 are the same. All of the power output obtained from the two tubes may be supplied to the output circuit, except for that portion fed back to the input circuits of the two tubes by means of the voltage divider R_3R_4 and the feed-back path including R_1 , R_2 and R_5 . However, the impedance of these circuits, particularly that of R_3 and R_5 , may be made so large compared to that of the load plate-to-cathode impedance that the amount of power absorbed by the feedback paths is negligibly small. For example, the plate-to-cathode load impedance may be of the order of magnitude of 2500 ohms, whereas that of R_3 and R_5 is of the order of magnitude of 500,000 ohms. Hence, the amount of power taken by the feedback paths would be one-half of one per cent of the total power available, which is negligibly small.

In Fig. 2 is shown one modification of the invention. In this figure the input signal for V_2 is obtained from a tapped connection on the primary of the transformer, instead of by means of the voltage divider of Fig. 1 which at the present time is slightly more economical. The degenerative feedback connection also differs from that of Fig. 1 in that use is made of a secondary winding of the transformer, which may conveniently be the output winding or an extension thereof, to obtain a feedback voltage in the input circuit. The phase of the feedback voltage must be opposite that of the input signal, and will decrease the overall gain of the amplifier, and hence is less desirable than the circuit of Fig. 1.

It will be apparent that various other modifications of the invention are possible without departing from the spirit and scope of the invention, and therefore the invention is not confined to the specific forms herein described.

I claim:

1. In an amplifier circuit, a load circuit including a winding, a plurality of space discharge devices each having input and output circuits and characterized in that the output voltage of each of said devices is of substantially opposite phase with respect to the input voltage thereof, connections for including a part of the winding in the output circuit of one space discharge device, connections between another part of the winding and the input circuit of the said one discharge device for supplying to the said input circuit a non-degenerative signal voltage of opposite phase.

with respect to the voltage in the output circuit of said one discharge device, connections for including part of said winding in the output circuit of another space discharge device, and means for degeneratively coupling the input and output circuits of said other discharge device.

2. In an amplifier circuit, a load circuit including a winding, a plurality of space discharge devices each having input and output circuits, connections for including a part of the winding in the output circuit of one space discharge device, connections between another part of the winding and the input circuit of the said one discharge device, a voltage divider included in said last-named connections for applying a non-degenerative signal to the input circuit of said one device, connections for including part of said winding in the output circuit of another space discharge device, and a degenerative connection 20 for coupling the input and output circuits of said other discharge device.

3. In an amplifier circuit, a load circuit including a winding, a plurality of space discharge devices each having input and output circuits, connections for including a part of the winding in the output circuit of one space discharge device, connections between another part of the winding and the input circuit of the said one discharge device, a voltage divider included in said last-named connections for applying a desired signal to the input circuit of said one device, a condenser connected across a portion of the voltage divider, connections for including part of said winding in the output circuit of another space discharge device, and a degenerative connection 35 for coupling the input and output circuits of said other discharge device.

4. In an amplifier circuit, a load circuit including a winding, a plurality of space discharge devices each having a cathode, a control grid, a screen grid, and an anode, and characterized in that the output voltage of each of said devices is of substantially opposite phase with respect to the input voltage thereof, connections for including a part of the winding in circuit with the anode and cathode of one space discharge device, connections for including another part of the winding in circuit with the cathode and control grid of said one device so as to apply to said control grid a non-degenerative voltage in phase opposition with respect to the voltage on the anode of said one device, connections for including part of said winding in circuit with the anode and cathode of another space discharge device to 55 form an output circuit, means for supplying electrical energy to the anodes and screen grids of each of said discharge devices, an input circuit including a source of signal energy connected to the cathode and control grid of said other device, 60 and a degenerative connection for coupling the input and output circuits of said other discharge device.

5. In an amplifier circuit, a load circuit including a winding, a plurality of space discharge devices each having input and output circuits, connections for including a part of the winding in the output circuit of one space discharge device, connections between another part of the winding and the input circuit of the said one discharge device, connections for including part of said winding in the output circuit of another space discharge device, an additional space discharge device having an output circuit connected to the input circuit of said other device, and a conductive impedance connected be-

tween the output circuit of said other device and the output circuit of said additional device, for degeneratively coupling the input and output circuits of said other discharge device.

6. In an amplifier circuit, a load circuit including a winding, a plurality of space discharge devices each having input and output circuits, connections for including a part of the winding in the output circuit of one space discharge device, connections between another part of the 10 winding and the input circuit of the said one discharge device, connections for including part of said winding in the output circuit of another space discharge device, an additional space discharge device having an output circuit connected 15 to the input circuit of said other device, and a resistance connected between the output circuit of said other device and the output circuit of said additional device, for degeneratively coupling the input and output circuits of said other discharge 20 device.

7. In an amplifier circuit, a load circuit including a winding, a pair of space discharge devices each having a cathode, a control grid, a screen grid and an anode, connections between the 25 ends of said winding and said anodes, a connection including a source of electrical energy between the mid-point of said winding and both of said cathodes, a circuit for supplying electrical energy connected to said cathodes and said 30 screen grids, a voltage divider connected to the anode-cathode circuit of one of said devices, a circuit for deriving an input signal from said voltage divider and supplying it to the control grid of said other device, an additional space 35 discharge device having an output circuit, a circuit for supplying a signal from said output circuit to the control grid of said one device, and a resistance connected in circuit with the anode of said one device and the output circuit of said 40 additional device for degeneratively coupling the anode-to-cathode and control grid-to-cathode circuits of said one device.

8. In an electrical system, a pair of space discharge devices, each having a cathode, an anode 45 and a control element, an output circuit including a winding and means for connecting one end of said winding to one anode and the other end of said winding to the other anode, means for supplying electrical energy to said devices, an input 50 circuit for one of said devices connected between the cathode and the control element thereof, means for deriving a signal from the output circuit of said one device and for applying the derived signal between the cathode and control element of the other device, and a degenerative connection between the output and input circuits of said one device.

9. In an amplifier circuit, a source of signals comprising unbalanced or single-sided circuits, a balanced or double-sided circuit comprising a pair of space discharge devices each having input and output circuits, coupling means for applying signals from said source to the input circuit of one of said space discharge devices, means for deriving signals from the output circuit of said one space discharge device, coupling means for applying said derived signals to the input circuit of the other of said spaced discharge devices, a load for said space discharge devices, and a connection for degeneratively coupling the output and input circuits of said one space discharge device.

10. In an amplifier circuit, a source of signals comprising unbalanced or single-sided circuits, a 75

balanced or double-sided circuit comprising a pair of space discharge devices in push-pull relation, said devices including control grid and plate electrodes, coupling means for applying signals from said source to the control grid of one of said space discharge devices, means for deriving signals of reversed phase from the plate circuit of said one space discharge device, means for applying said reversed phase signals to the control grid of the other of said space discharge devices, a balanced or double-sided load for said space discharge devices, and means connected between the plate and grid circuits of said one space discharge device for degeneratively coupling the output and input circuits thereof.

11. In an amplifier circuit, a load impedance, a plurality of space discharge devices each having input and output circuits, connections for including a part of the load impedance in the output circuit of one space discharge device, connections between another part of the load impedance and the input circuit of the said one discharge device, a voltage divider included in said last-named connections for applying a non-degenerative signal to the input circuit of said one device, connections for including part of said load impedance in the output circuit of another space discharge device, and a degenerative connection for coupling the input and output circuits of said other discharge device.

12. In an electrical system, a pair of space discharge devices, each having a cathode, an anode and a control element, an output impedance, and means for connecting one end of said impedance to one anode and the other end of said impedance to the other anode, means for supplying electrical energy to said devices, an input circuit for one of said devices connected between the cathode and the control element thereof, means for deriving a signal from the output circuit of said one device and for applying the derived signal between the cathode and control element of the other device, and a degenerative connection between the output and input circuits of said one device.

13. In an amplifier circuit, a load impedance, a plurality of space discharge devices each having input and output circuits and characterized in that the output voltage of each of said devices is of substantially opposite phase with respect to the input voltage thereof, connections for including a part of the load impedance in the output circuit of one space discharge device, connections between another part of the load impedance and the input circuit of the said one discharge device for supplying to the said input circuit a non-degenerative signal voltage of opposite phase with respect to the voltage in the output circuit of said one discharge device, connections for including part of said load impedance in the output circuit of another space discharge device, and means for degeneratively coupling the input and output circuits of said other discharge device.

14. In an amplifier circuit, a load impedance, a plurality of space discharge devices each having input and output circuits and characterized in that the output voltage of each of said devices is of substantially opposite phase with respect to the input voltage thereof, connections for including a part of the load impedance in the output circuit of one space discharge device, connections between another part of the load impedance and the input circuit of the said one discharge device for supplying to the said input circuit a non-degenerative signal voltage of opposite phase with respect to the voltage in the output circuit of said one discharge device, connections for including part of said load impedance in the output circuit of another space discharge device, and means for degeneratively coupling the input and output circuits of said other discharge device.
